[57] CLAIM

The ornamental design for an outer sole for footwear, as shown.

DESCRIPTION

FIG. 1 is a bottom plan view of an outer sole for footwear showing my new design, it being understood that the small circle pattern is continuous;

FIG. 2 is a top plan view thereof;

FIG. 3 is a left side elevational view thereof;

FIG. 4 is a right side elevational view thereof;

FIG. 5 is a cross sectional view taken along the line 5—5 of FIG. 1; and

FIG. 6 is a cross sectional view taken along the line 6—6 of FIG. 1.
